Alva K. Hinchman.
INVENTOR

BY *Victor J. Evans*

ATTORNEY

Jno. Babin, Jr.
WITNESS:

UNITED STATES PATENT OFFICE.

ALVA K. HINCHMAN, OF GLOUCESTER CITY, NEW JERSEY, ASSIGNOR TO J. H. MALONE,
OF DREXEL HILL, PENNSYLVANIA.

AUTOMATIC PRESSURE-REGULATOR VALVE.

Application filed September 18, 1922, Serial No. 588,946. Renewed May 11, 1928.

This invention relates to relief valves, and one of the principal objects of the invention is to produce a device of this nature which shall be automatic in its seating and unseating.

Another object is to produce a device of this nature having an adjustable fulcrum.

Another object is to produce a device of this nature which shall be simple and practical of construction, cheap to manufacture, and highly efficient for the purpose for which it is designed.

With these and other objects in view as will be more apparent, the invention consists in certain novel construction and combination and arrangement of parts, the essential features of which are hereinafter fully described, are particularly pointed out in the appended claim, and are illustrated in the accompanying drawing, in which:—

Figure 1—is a longitudinal sectional view partly in elevation showing one embodiment of my improvement.

Figure 2—is a similar view showing a modified form of my invention.

Like characters of reference refer to like parts in all the views.

Referring to the drawing in detail, 10 represents a main pipe or steam line which is provided with valve bodies 11 and 12. The body 11 is provided with a valve seat 13 on which is seated a valve member 14 having a stem 15 provided at its upper end with a clevit 16.

35 The member 12 is provided at one side with a tubular extension 17 in which operates a piston 18, the rod 19 of which projects upwardly parallel with the valve rod 15 and is provided at its upper end with a clevit 20. A bar or link 21 is pivoted at its slotted opposite ends 21' in the clevites 16 and 20, and at an intermediate point passes through a clevit 22 pivotally connected to an upright 23 which is supported by a

40 collar or ring 24 movable along the pipe 10 and adapted to be secured in any desired position thereon by a thumb-screw 25. A thumb screw 26 is provided in clevit 22 so as to permit adjustment according to the 45 position of the valves and the consequent inclination of the bar 21.

The operation of the above described mechanism is as follows:—

When the pressure in the member 11 under the valve 14 becomes sufficiently greater than the pressure in the member 12, the valve 14 is lifted, and the piston 18 is lowered in the cylindrical member 17. The steam now rushes through and gradually builds up a pressure under piston 18. When this pressure is sufficiently great it forces the piston 18 upwardly and thereby effects the re-seating of the valve member 14. The amount of pressure necessary to effect the operation described may be controlled by the moving of the fulcrum 23—26 along the pipe 10.

In the form shown in Figure 2 the member 11^a is provided with a valve 14^a having ways or ports 30 therethrough and adapted to register with ways or ports 31 in the valve seat 13^a. The position of the cylindrical member 17^a is the reverse of that shown in Figure 1 and in consequence the piston rod 19^a is considerably longer. The balance of the mechanism is substantially the same as shown in Figure 1.

In this form of the invention, when the pressure builds up above the valve member 14^a it is forced down until the ports 30 and 31 register so that the steam may pass through the line. In due time the pressure will build up above the piston 18 and will force it down in member 17^a whereby the valve 14^a will be raised until the ports 30 and 31 are no longer in register.

While I have described what I deem to be the most desirable embodiments of my invention, I do not limit myself to the specific details of construction of material, nor to anything less than the whole of my invention as defined in the appended claim.

What I claim:—

In an automatic pressure regulator valve, the combination with a steam line, of a plunger valve for controlling the passage of steam therethrough, a cylinder having communication with the steam line, a pressure operated piston movable in said cylinder, an upstanding stem on said plunger valve, an upstanding stem on said piston, a supporting yoke having a vertical standard

thereon adjustably carried by said steam line for lateral movement from a point intermediate said valve and piston, means for holding the yoke in different position, a 5 clevis bracket having a transverse opening in its upper end pivoted to the free end of said standard, a bar having slots adjacent its ends slidably and, extending through

said opening, clevis brackets on said stems for slidably pivoting the stems to the 10 slotted ends of the bar, and means carried by the first clevis bracket to retain such first bracket in adjusted relation to said bar.

In testimony whereof I affix my signature.

ALVA K. HINCHMAN.
